Warren W. House
His ATTORNEY.

UNITED STATES PATENT OFFICE.

WILLIAM L. PATTISON, OF ROSEDALE, KANSAS.

STAIR.

Application filed September 13, 1922. Serial No. 587,956.

To all whom it may concern:

Be it known that I, WILLIAM L. PATTISON, a citizen of the United States, residing at Rosedale, in the county of Wyandotte and State of Kansas, have invented a certain new and useful Improvement in Stairs, of which the following is a specification.

My invention relates to improvements in stairs. It relates particularly to a stair tread.

One of the objects of my invention is to provide a novel stair tread, which has a maximum of strength with a minimum of weight and material, which is cheap to make, strong and durable.

My invention provides further a novel nosing bar, and novel means for supporting thereon a tread grating.

The novel features of my invention are hereinafter fully described and claimed.

In the accompanying drawing, which illustrates the preferred embodiment of my invention,

Fig. 1 is a top view of two of my improved treads shown mounted on two stringers, which are broken away.

Fig. 2 is a vertical section on the line 2—2 of Fig. 1, the view being enlarged.

Fig. 3 is a vertical section on the broken line 3—3 of Fig. 1.

Fig. 4 is an enlarged vertical section on the line 4—4 of Fig. 1.

Similar reference characters designate similar parts in the different views.

1 designates the usual two stringers, such as are commonly used in fire escapes, to which my invention is particularly well adapted for use.

2 designates a nosing bar from the front portion of which extend rearwardly two arms 3, fastened by bolts 4 to the stringers 1 respectively. The arms 3 are inwardly turned at their rear ends, to form the portions 5. Extending through the arm portions 5 respectively of the nosing bar and through the front portion of said bar are two transverse horizontal bolts or bars 6, which may be threaded and provided with nuts 7 at their rear ends.

Supported on the bars or bolts 6 is a tread grating 8, which is located between the arm portion 5 and the front portion of the nosing bar to which the rear and front sides of

the tread grating are respectively secured by bolts 9, or other suitable means.

It will be noted that the grating 8 at its ends terminates short of the stringers 1 and is wholly supported by the nosing bar. As it is supported by the bars or bolts 6, the grating may have relatively shallow depth, while affording sufficient strength for its purpose. This construction affords a maximum of strength with a minimum of material, cost and weight.

By having the nosing bar of substantially rectangular form, a very strong construction is afforded, which is rigid and furnishes secure means for attachment to the stringers and to the grating.

I do not limit my invention to the structure shown and described, as many modifications, within the scope of the appended claims, may be made, without departing from the spirit of my invention.

What I claim is:—

1. A stair tread comprising a nosing bar having a front portion and two arms which extend rearwardly and then inwardly toward each other, the arms being adapted to be supported by two stringers respectively, and a tread grating attached to and supported by said front portion and said inwardly extending portions of said arms, substantially as set forth.

2. A stair tread comprising a nosing bar having a front portion and two arms which extend rearwardly and then inwardly toward each other, the arms being adapted to be supported by two stringers respectively, two bars supported respectively by said inwardly extending portions of said arms and said front portion, and a tread grating supported on said bars, substantially as set forth.

3. A stair tread comprising a nosing bar having a front portion and two arms which extend rearwardly and then inwardly toward each other, the arms being adapted to be attached to and supported by two stringers respectively, two bars supported respectively by said inwardly extending portions and said front portion, and a tread grating resting on said bars and attached at its front and rear sides respectively to said front portion and to said inwardly extending portions, substantially as set forth.

4. A stair tread comprising a nosing bar, arms adapted to be respectively secured to and a tread grating attached at its front two stringers, the rear ends of said arms and rear sides to and supported by said arms extending inwardly toward each other, substantially as set forth.
5. A nosing bar of the kind described comprising a bar having a front portion provided with two rearwardly extending

In testimony whereof I have signed my name to this specification.

WILLIAM L. PATTISON.
